UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,311,607.

Specification of Letters Patent. Patented July 29, 1919.

Application filed August 31, 1917. Serial No. 189,044.

To all whom it may concern:

Be it known that I, LLOYD V. LEWIS, a citizen of the United States, residing at Edgewood borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus for governing the speed of railway cars and trains.

I will describe one form of apparatus embodying my invention and will then point out the novel features thereof in claims.

In the accompanying drawings, Figure 1 is a diagrammatic view showing a railway track having applied thereto one form of 20 controlling apparatus embodying my invention. Fig. 2 is a view showing one form and arrangement of apparatus carried by a car or train and arranged to coöperate with the trackway apparatus shown in Fig. 1, and 25 also embodying my invention. Fig. 3 is a detail view showing one means for connecting a portion of the apparatus shown in Fig. 1 with an axle of the vehicle.

Similar reference characters refer to similar parts in each of the views.

Referring first to Fig. 1, the reference characters 1, 1 designate the track rails of a railway, which rails are divided by suitable means, such as insulated joints 2, into a 35 plurality of successive block sections C—D, D—E, E—F, etc. Traffic over the railway normally moves in the direction indicated by the arrow. Each block section is provided with a track circuit comprising the 40 rails of the section, and a source of signaling current 3, and a relay R connected with the rails of the section adjacent the exit and entrance ends respectively. Each section may be provided with a signal S 45 which signals are controlled by the relays R, although these signals are not essential to the remainder of the system. If signals are provided, each one is adapted to indicate

“stop” when the corresponding section is occupied, “caution” when the corresponding section is unoccupied and the section next in advance is occupied, and “proceed” when the corresponding section and the section next in advance are unoccupied. The circuits for controlling these signals form no 55 part of my invention, and hence they are omitted from the drawing for the sake of clearness.

Located adjacent the entrance end of each block section are two trackway magnets A 60 and B, these magnets preferably being located side by side between the rails, as shown in Fig. 2. Each magnet (see Fig. 2) comprises a U-shaped core 4 of magnetizable material, such as soft iron, the legs of which 65 project upwardly, and a winding 5 on the core for energizing the same. Located on the train (Fig. 2) are two magnets A³ and B³, which pass in inductive relation to the trackway magnets A and B, respectively, as 70 the train proceeds along the track. Each of the train-carried magnets is similar to the trackway magnets except that the legs of the core project downwardly. It will be seen that as the train passes over the trackway magnets, current will be induced in the winding of each train magnet if the corresponding trackway magnet is energized, but not if the corresponding trackway magnet is deenergized.

80 Referring again to Fig. 1, the trackway magnet A at the entrance of each section is controlled by the track relay for such section and also by the track relay for the section in advance, so that this magnet is 85 energized only when both of these sections are unoccupied. For example, the circuit for magnet A at the entrance of block section C—D is from battery 6 at location D, through wire 7, contact 8 of relay R at 90 location D, wire 9, contact 10 of relay R at location C, wire 11, winding of magnet A, wire 12, common wire 0, wire 17 to battery 6. The trackway magnet B at the entrance 95 of each block section is controlled by the track relay of such block section so that this

magnet is energized when such section is unoccupied, even though the section next in advance may be occupied. For example, the circuit for magnet B at the entrance to block 5 section C—D is from the adjacent battery 6, through wire 7, contact 8 of relay R at location C, wire 13, winding of magnet B, wire 12, common wire O and wire 17 to battery 6.

10 Located at intervals in each block section are other trackway magnets A' and A², all of which are in alignment with magnets A, so that they are in inductive relation with the train-carried magnet A³ as the train 15 passes along the track. The last magnet in each block section is designated A², whereas the magnets between this and the magnet A at the entrance end of the block section are designated A'. Each magnet A' is constantly 20 energized, the circuit being from battery 6 at the next signal location through wire 14, one of the wires 14^a, magnet A', wire 15, common wire O and wire 17 to battery 6. In other words, the magnets A' in 25 each section are connected in multiple across wires 14 and O. Magnet A² in each block section is controlled by the relay R for the section next in advance, so that this magnet is energized or not, according as the section next in advance is unoccupied or is occupied. For example, the circuit for magnet A² in block section C—D is from battery 6 at location D, through wire 7, contact 8 of relay R, wires 9 and 16, magnet A², wire 30 18, common wire O, and wire 17 to battery 6.

The spacing of the trackway magnets A, A' and A² depends upon the constant of a run-down device constituting part of the train-carried apparatus, as will be explained 40 hereinafter.

Referring now to Fig. 2, I have shown at the right-hand end of the drawing a device P which I will term a "speed responsive device." This device comprises a 45 box 19, in two opposite walls of which is journaled a hollow shaft 20. This shaft carries at its outer end a spur gear 21, which is connected through suitable gearing with a wheel or axle of the vehicle, so that 50 while the vehicle is in motion the shaft 20 is constantly rotated at a speed proportional to the speed of the vehicle. The part of the shaft 20 which is inside the box 19 is provided with two diametrically disposed 55 arms in which are pivoted the two bell cranks 23, 23 of a centrifuge. These bell cranks coat with a head 25, which is freely mounted on a stem 24 passing through the shaft 22. The head 25 coats with another 60 head 26 fixed to the stem 24, the two heads being separated by a ball bearing to reduce friction. Suitable means are provided, as hereinafter described, for biasing the stem 24 toward the right, thus opposing the

natural tendency of the centrifuge to open 65 while the vehicle is in motion. The right-hand end of the stem 24 constitutes a valve 27 which controls the vehicle brakes in any suitable manner, the control being such that the brakes are applied when this valve is 70 opened. When the centrifuge is closed, the valve 27 is closed, but when the centrifuge opens, it moves the stem 24 to the left and so 75 opens valve 27.

The means for biasing stem 24 toward the 80 right is, in the form here shown, arranged to exert three different pressures on this stem, thus imposing three different speed limits on the vehicle. This means is as follows:

Attached to the box 19 is a cylinder 37 and between the two is a diaphragm 30 of suitable flexible material, this diaphragm being held in place between flanges on the box and on the cylinder. The left-hand end of 85 stem 24 is provided with a head 28 bearing against the diaphragm 30, whereby when the vehicle is in motion this head tends to bend the diaphragm to the left due to the force exerted by the centrifuge. Within the cylinder 37 is a spring 31 one end of which rests against a head 29 on the opposite side of the diaphragm from the head 28 and the other end of which spring rests against a piston 32 adapted to reciprocate in the cylinder. 90 The spring 31 is so adjusted that when the piston is at the left-hand end of its cylinder, as shown in the drawing, the pressure exerted on the stem 24 through the diaphragm 30 is of such value that as long as 95 the vehicle does not exceed a predetermined low speed, for example, 15 miles per hour, the centrifuge will not open, but that if the vehicle exceeds this speed, the centrifuge will overcome the action of the spring and 100 will open valve 27, thus causing an application of the brakes. This spring then when fully expanded, as shown, imposes on the vehicle what I will term a "low speed limit."

34 designates a pipe for at times admitting fluid pressure to the cylinder 37 on the left-hand side of piston 32. When this occurs, the piston is driven to the right-hand end of the cylinder, thus compressing the spring 31 and so increasing the pressure exerted by this spring against the diaphragm 30. The pressure opposing the centrifuge is then such as to permit the vehicle to travel at a speed not exceeding a predetermined intermediate value, for example, 35 115 miles per hour, without opening the centrifuge, and so it imposes what I will term an 120 "intermediate speed limit".

In order to permit the vehicle to travel at high speed, such for example, as 60 miles 125 per hour, without opening the centrifuge, I provide a pipe 33 which opens into the cylinder 37 directly on the left-hand face

of diaphragm 30. This pipe is at times supplied with fluid pressure and when so, it causes a high pressure to be exerted directly on the diaphragm, which pressure permits the vehicle to travel at high speed without causing the centrifuge to open. This pressure, then, imposes what I will term a "high speed limit".

Fluid pressure, usually air, is at times supplied to pipe 34 from a reservoir or other suitable source, this supply being controlled by a valve 36, which in turn is controlled by a magnet M', which I will term the "intermediate speed magnet". This magnet and valve are so arranged that when the magnet is deenergized, the valve disconnects the pipe 34 from the source of pressure and connects the pipe with atmosphere through an exhaust port 38, but that when the magnet is energized, the valve connects the pipe 34 with the source of fluid pressure and closes the exhaust port. In order to cause a gradual decrease in the pressure exerted against the piston 32 when magnet M' is deenergized, I provide a timing reservoir T' connected with the pipe 34. This reservoir is, of course, charged with fluid pressure when the pipe 34 is connected with the source, but when the pipe 34 is disconnected from the source and opened to atmosphere the pressure in the reservoir T' decreases gradually because of the small area of the ports in valve 36, and so causes a gradual decrease in the pressure exerted against the piston. The timing reservoir T' and the small ports in the valve thus constitute what may be termed a secondary run-down device.

The supply of fluid pressure to the pipe 33 is controlled in a similar manner by a valve 35 and a magnet H', which latter I will term the "high speed magnet". The pipe 33 is provided with a timing reservoir T, the purpose of which is the same as that of the reservoir T', this timing reservoir T and the small ports in valve 35 constituting another secondary run-down device.

The intermediate speed magnet M' is controlled by an intermediate speed relay M, the circuit being from one terminal B' of a source of current through wire 65, contact 39 of relay M, wire 40, magnet M', wire 41 to the other terminal O' of the source of current. The source of current itself and the parts of the circuit which do not pass through the apparatus shown in the drawing, are omitted for the sake of simplicity. It will be seen that magnet M' is energized or deenergized according as relay M is energized or not. The high speed magnet H' is similarly controlled by a contact 42 of a high speed relay H, the circuit being obvious from the drawing.

Relays H and M are controlled by two relays *a* and *b* and also by a run-down de-

vice J. I will first describe the run-down device, and will then explain the control of the relays H and M.

The run-down device J comprises an elongated casing 53, in which is journaled a gear wheel 54. This wheel carries a pin 54^a, 70 which coacts with a contact 104 to open this contact when the wheel 54 occupies the position in which it is shown in the drawing. When the wheel 54 is rotated in the direction of the arrow from the position in which it is shown, contact 104 closes due to its own bias. Fixed to the gear 54 is a spur gear 59 which meshes with a rack 60 mounted to reciprocate in the casing 53. This rack is biased toward the right, that is, to the position in which it is shown, by a spring 61, but may be reset, that is, moved to the left in opposition to the action of the spring, by means which I will explain hereinafter. Movement of the rack 60 and gear 54 in response to the action of the spring 61 is restrained by operatively connecting the gear with a wheel or axle of the vehicle, so that this movement takes place in proportion to the progress of the vehicle along the track. 90 This connection comprises a gear 55 meshing with gear 54 and connected with a gear 56 through a clutch 57. Gear 56 coacts with a worm 58 fastened to a shaft to which is also fixed a ratchet wheel 105. As shown in 95 Fig. 3, this ratchet wheel is driven intermittently in one direction by a pawl 106 which in turn is reciprocated by a connecting rod 107. This rod may derive its motion from some reciprocating part of the vehicle running gear, or, as here shown, from a crank 108 on a shaft 109 geared to an axle of the vehicle. The purpose of the mechanism between the shaft 109 and the worm 58 is to provide that the direction of rotation of 105 the worm shall be the same irrespective of the direction of movement of the vehicle. The purpose of the worm 58 is to provide an irreversible driving connection between ratchet wheel 105 and gear 56 so that gear 110 115 120 125 130 gear 54 cannot rotate under the influence of the spring 61 except as motion is imparted to the worm due to the movement of the vehicle. The clutch 57 is so arranged that gear 54 may be turned freely in the direction of the arrow, that is, in opposition to the action of spring 61, to reset the device, but that movement of this gear in the other direction under the influence of the spring is restrained by the worm 58 and so can take place only in proportion to the travel of the vehicle. The means here shown for resetting the rack and gear 54, that is, for moving the rack to the left in opposition to the action of the spring, comprises a piston 62 sliding in a cylinder 53^a constituting part of the casing 53. The right-hand face of this piston 62 is at times connected with the

source of fluid pressure by a valve 63, which in turn is controlled by a magnet W. When this magnet is deenergized, the right-hand end of the cylinder 53 is connected with atmosphere through a port 64, but when the magnet is energized the valve 63 is reversed to disconnect the cylinder from atmosphere and connect it with the source of fluid pressure.

10 The operation of the run-down device J is as follows:

As the vehicle proceeds along the track, gear 54 is gradually permitted to rotate to such position that pin 54^a opens contact 42, 15 as shown in the drawing. This position I will term the "ultimate condition" of the device. If, then, the magnet W is momentarily energized, fluid pressure is admitted to the right-hand end of cylinder 53^a, thus 20 rotating gear 54 in the direction indicated by the arrow and so resetting the device, whereupon it again resumes its change toward its ultimate condition.

Each relay *a* and *b* is provided with two 25 windings. The upper winding of relay *a* is connected directly with the winding of the train-carried magnet A³, whereas the upper winding of relay *b* is connected directly with the winding of train-carried magnet 30 B³. It will be seen, therefore, that when either train-carried magnet A³ or B³ passes over an energized trackway magnet, the corresponding relay *a* or *b* will be momentarily energized. In order to keep the contacts of 35 relays *a* and *b* closed for an appreciable interval of time after such energization, I provide two slow-releasing relays *a'* and *b'*, which relays coat with relays *a* and *b*, respectively, in the following manner. While 40 relay *a* is deenergized, relay *a'* is energized. The circuit being from terminal B' of a source of current through wires 75 and 66, lower point of contact 67 of relay *a*, wire 68, winding of relay *a'*, and wires 69 and 76 to 45 the terminal O' of the source of current. When the upper winding of relay *a* is momentarily energized, the contacts of this relay are, of course, picked up, whereupon the lower winding of the same relay becomes energized through the following circuit: from 50 terminal B' of a source of current, through wires 75 and 66, upper point of contact 67, wire 71, lower winding of relay *a*, wire 72, contact 73 of relay *a'*, and wires 74 and 76 to the terminal O' of the source of current. The picking up of a relay *a* opens the circuit 55 for relay *a'* at contact 67, but inasmuch as this latter relay is slow-releasing in character, its contact 73 remains closed for an appreciable interval of time, so that relay *a* likewise remains energized for the same period of time. When relay *a'* releases, it opens at contact 73 the circuit for the lower winding of relay *a*, whereupon this relay

likewise releases and the consequent reversal 65 of contact 67 closes the circuit for relay *a'*, which relay then again becomes energized. Relays *a* and *a'* are then in the condition in which they are shown in the drawings.

The co-operation of relays *b* and *b'* is exactly the same as co-operation of relays *a* and *a'*, the circuit for relay *b'* being controlled by contact 70 of relay *b*. Relays *a* and *b* are preferably of the so-called "Hughes" type, 70 that is, are provided with permanently magnetized cores and armatures, so that these relays will respond to close their contacts only when energized by an impulse in the proper direction. When passing over a track magnet A or B, the induced current impulse 75 will be in one direction while approaching the track magnet and in the opposite direction while withdrawing from the track magnet. The direction of current flow through the upper windings of relays *a* and *b* is so chosen that these relays will be energized as coils A³ or B³ are withdrawn from track 80 magnets A and B and the direction of current flow through the lower windings of *a* and *b* is likewise chosen to be that which 85 will cause these relays to remain picked up.

The control of magnets H and M and of the run-down device J by the relays *a* and *b*, will be traced out in describing the operation of the system as a whole, which operation is as follows:

Referring to Fig. 1, block section E—F is occupied by a car or train U, so that signal S for this block section indicates stop. Consequently, magnets A and B at the entrance end of this block section are both deenergized because the relay R for the section is open. Magnet A³ in block section D—E is deenergized, and magnet A at the entrance of this section is likewise deenergized. Magnet B, however, at the entrance of section D—E is energized. All of the trackway magnets for section C—D, including the two magnets at the entrance end of this section, are energized, and all the magnets A' for 100 sections D—E and E—F are energized.

I will now assume that a second car or train passes through the stretch of track shown in Fig. 1 and that such car or train is equipped with the apparatus shown in 105 Fig. 2. I will further assume that as such car or train approaches section C—D, both of its relays H and M are deenergized. As the train passes over magnets A and B at the entrance of section C—D, both relays *a* and *b* will become energized. High speed magnet H is then energized, the circuit being from battery, through contact 77 of relay *b'*, wire 78, contact 79 of relay *a'*, wire 80, upper point of contact 81 of relay *a*, 110 wire 82, contact 83 of relay *b*, wires 84 and 85, relay H, and wires 86 and 50 to common wire O'. As soon as relay H picks

up, magnet W of the run-down device J is energized through the following circuit: from battery, through contact 77 of relay b', wire 78, contact 79 of relay a', wires 80 and 87, upper point of contact 88 of relay a, wire 89, upper point of contact 90 of relay b, wire 91, upper point of contact 92 of relay H, wire 93, lower point of contact 94 of relay M, wire 95, magnet W, and wire 96 to common wire O'. The energization of magnet W causes the run-down device J to be reset away from its ultimate condition, whereupon this device again begins to run down as the train proceeds along the track, because the circuit of magnet W is opened as soon as a' or b' is deenergized. Relay H, having thus been energized, is held closed after relays a and b open, the holding circuit being from battery, through contact 104 of run-down device J, wires 43 and 43^a, contact 51 of magnet M, wire 97, contact 52 of relay H, wire 85, relay H, and wires 86 and 50 to common wire O'. Relay H thus remains energized as long as contact 104 of run-down device J remains closed. The energization of relay H causes high speed magnet H' to become energized, and this in turn actuates valve 35 to admit fluid pressure to the diaphragm 30 of the speed responsive device P, so that the train may proceed at high speed (60 miles per hour).

As the train proceeds along the track, gear 54 of run-down device J moves slowly toward the position wherein pin 54^a will open contact 42, but just before this position is reached the train passes over the first trackway magnet A' in block section C—D. This magnet being energized, a momentary impulse is induced in train-carried magnet A², which causes energization of relay a. Magnet W of run-down device J is then again energized through the following circuit: from battery through contact 77 of relay b', wire 78, contact 79 of relay a', wires 80 and 87, upper point of contact 88 of relay a, wire 89, lower point of contact 90 of relay b, wires 95^a and 95, magnet W, and wire 96 to common wire O'. The run-down device J is thus restored before its contact 104 is opened, and so this contact continues to hold closed the holding circuit for relay H.

The same operation takes place as the train passes over the second trackway magnet A' in block section C—D, and likewise the same operation takes place as the train passes over magnet A² in this same section.

As the train enters section D—E, its relay b becomes energized, but relay a remains open, because trackway magnet B is energized but magnet A is deenergized. During the period that relay b is closed, relay H becomes deenergized, relay M is ener-

gized and magnet W of the run-down device J is likewise again energized to restore this device. The circuit for relay M is from battery, through contacts 77 and 79, wire 80, lower point of contact 81 of relay a, wire 98, contact 99 of relay b, wires 100 and 48, relay M, wires 49 and 50 to common wire O'. The closure of relay M opens at contact 51 of this relay the holding circuit for relay H so that the latter relay becomes deenergized. Magnet H' thus becomes deenergized and magnet M' becomes energized. The pressure upon the left-hand side of diaphragm 30 then gradually reduces, thereby gradually reducing the speed limit imposed upon the vehicle by the speed responsive device P, this reduction being gradual because of the timing reservoir T. Magnet M' being energized, however, fluid pressure is admitted to the left-hand end of cylinder 37, through pipe 34, whereby the train may proceed at the intermediate speed of 35 miles per hour without being brought to a stop. Relay M is provided with a holding circuit to keep this relay closed after relay b opens, this holding circuit being from battery, through contact 104 of run-down device J, wire 43, contact 44 of relay H, wire 45, contact 46 of relay M, wires 47 and 48, relay M, wires 49 and 50 to common wire O'. The circuit for magnet W is in this case from battery through contact 77, wire 78, contact 79, wires 80 and 87, back contact 88 of relay a, wire 101, front contact 102 of relay b, wire 103, front contact 94, wire 93, back contact 92, wires 95^a and 95, magnet W, wire 96 to common wire O'.

When the train passes over the first magnet A' in block section D—E, relay a is momentarily energized, whereupon the run-down device J is reset through the circuit first traced for this device, and the same thing is true as the train passes over the second trackway magnet A' of this block section. When, however, the train reaches magnet A² in block section D—E, which is now deenergized, the train-carried relay a does not become energized. Consequently, when the train has passed a short distance beyond this magnet, the pin 54^a of the run-down device J opens contact 104, whereupon relay M becomes deenergized, thus deenergizing magnet M' so that the left-hand end of cylinder 37 of the speed responsive device P is disconnected from the source of fluid pressure and connected with atmosphere. The pressure now gradually flows out of the timing reservoir T', thus gradually reducing the speed limit to the low value which I have herein assumed to be 15 miles per hour. The train can now proceed at this speed until it comes within sight of the train U in block section E—F, or until it passes over an ener-

gized trackway magnet B. As the train passes over magnets A' in section E—F, relay a will be energized to restore run-down device J, but as magnets H and M are already deenergized they will remain in that condition and maintain the speed limit at 15 miles per hour. It will be seen, therefore, that as the train passes point E, the secondary run-down device comprising reservoir 10 T' is set into operation when the main run-down device J reaches its ultimate condition.

From the foregoing it will be seen that when the apparatus on the train has been set for either the high or the intermediate speed limit at the entrance of a block, it is maintained in such condition during the passage of the train through the block, or at least until the train reaches the last magnet A² in the block.

20 I will now assume that after the train had entered block section D—E, that is, after relay H had been deenergized and relay M energized, the train in section E—F passed out of this section into the next section in advance so that relay R for the section E—F became energized, thus energizing the trackway magnet A² in block section D—E and causing the signal S at the point E to assume the "caution" position. Then as the 25 following train passes over magnet A² in section D—E, the run-down device J is again reset to hold magnet M energized so that the train can continue at the intermediate speed limit until it reaches magnets A and B 30 at the entrance of block section E—F.

In this application I do not claim the broad combination of a run-down device which changes constantly toward an ultimate condition while the vehicle is in motion, and means located at intervals in the trackway for resetting such device away from its ultimate condition.

Although I have herein shown and described only one form and arrangement of apparatus and circuits embodying my invention, it is understood that various changes and modifications may be made therein within the scope of the appended claims without departing from the spirit and scope of 40 my invention.

Having thus described my invention, what I claim is:

1. Railway traffic controlling apparatus comprising speed-controlling means on a vehicle for imposing a plurality of different speed limits, and capable of being set to impose any one of said limits, a run-down device on the vehicle arranged to change progressively toward an ultimate condition, means controlled by said device for retaining said speed-controlling means in the condition in which it has been set until said device reaches the ultimate condition, and means including apparatus on the vehicle

and devices located at intervals along the 65 trackway for setting said speed-controlling means to impose a given speed limit and for resetting said run-down device away from ultimate condition.

2. Railway traffic controlling apparatus 70 comprising speed-controlling means on a vehicle for imposing a plurality of different speed limits, a run-down device on the vehicle arranged to change progressively toward an ultimate condition within a given interval after being reset, a trackway divided into block sections, means including apparatus on the vehicle and apparatus at the entrance end of each section for setting said speed controlling means to impose a given 75 speed limit and for resetting said run-down device, means controlled by said run-down device for maintaining said speed-controlling means in its set condition until the ultimate condition of said device is reached, and 80 apparatus for each block section spaced at intervals equal to or less than the interval of the run-down device for resetting said run-down device.

3. Railway traffic controlling apparatus 90 comprising means on a vehicle for imposing two or more different speed limits, two or more magnets for controlling said means one for each speed limit and arranged when energized to cause said means to impose the 95 corresponding speed limit, a run-down device on the vehicle arranged to change progressively toward an ultimate condition within a given interval after being reset, a trackway divided into block sections, means 100 including apparatus on the vehicle and apparatus located at the entrance of each block section for energizing one or another or none of said magnets according to traffic conditions in advance and for resetting said 105 run-down device, apparatus for each block section spaced at intervals less than the interval of said run-down device for restoring said device away from ultimate condition, and means controlled by said run-down 110 device for holding energized the magnet which is energized at the entrance end of the section.

4. Railway traffic controlling apparatus comprising a run-down device carried on a 115 vehicle and arranged to change progressively toward an ultimate condition, speed-controlling means governed by said run-down device and set into operation after the run-down device reaches its ultimate condition to impose a gradually reducing speed limit, and means located at intervals in the trackway for resetting said run-down device away from ultimate condition.

5. Railway traffic controlling apparatus 125 comprising a run-down device on the vehicle arranged to change progressively toward an ultimate condition, a secondary run-down

device also arranged to change progressively toward an ultimate condition, means controlled by said first device for releasing said secondary device when the first device reaches its ultimate condition, a speed responsive mechanism on the vehicle, vehicle-governing means controlled by said speed-responsive mechanism and by said secondary run-down device, and means including apparatus on the vehicle and apparatus located in the trackway for resetting both

of said run-down devices, the first device being arranged to automatically resume its change toward ultimate condition immediately after being reset.

15

In testimony whereof I affix my signature in presence of two witnesses.
